CLAIM

The ornamental design for a hair iron, as shown and described.

DESCRIPTION

FIG. 1 is a front, left side and top side perspective view of the hair iron of our design, in its closed configuration.

FIG. 2 is a front, right side and bottom side perspective view thereof.

FIG. 3 is a top plan view thereof.

FIG. 4 is a bottom view thereof.

FIG. 5 is a left side elevation view thereof, the right side being a mirror image thereof.

FIG. 6 is a front elevation view thereof.

FIG. 7 is a rear elevation view thereof.

FIG. 8 is a front, left side and top side perspective view of the hair iron of our design, in its opened configuration.

FIG. 9 is a front, right side and bottom side perspective view thereof.

FIG. 10 is a top plan view thereof.

FIG. 11 is a bottom view thereof.

FIG. 12 is a left side elevation view thereof and the right side being a mirror image thereof.

FIG. 13 is a front elevation view thereof; and,

FIG. 14 is a rear elevation view thereof.

Broken lines in the figures are for the purpose of illustrating portions of the hair iron which form no part of the claimed design.
